WEDGE KEY

Seth A. Crone, East Orange, N. J., assignor to
 Buffalo Brake Beam Company, New York, N. Y.,
 a corporation of New York

Application April 3, 1933, Serial No. 664,243

5 Claims. (Cl. 85—7)

This invention relates to a special construction of keys, such as is adapted to be used for readily connecting members together by the use of a relatively slight blow on one end of the key to drive it through an aperture in a connecting bolt which is resiliently cushioned, the key being specially constructed to wedge the bolt outwardly from the connected members and to allow the bolt to be locked by the key when it is fully driven into

10 the bolt.

In addition to such object the improved key is adapted to be readily released from the bolt by a relatively slight force which serves to slightly compress the resilient cushioning means, to allow

15 the key to be withdrawn.

A further object of the invention is to provide a key which may be readily driven home or released by the use of suitable force, or by relatively slight blows respectively against opposite 20 ends of the key, and to avoid the necessity of using heavy sledges or hammers, which cannot conveniently find access to the key for imparting a blow, while at the same time the improved key acts efficiently in all respects and holds the 25 connected members together in such way that they will not rattle and cause noises, especially when the connected members constitute parts of a structure, which is in rapid motion, as, for example, a railway car truck.

30 A further object is to provide a wedge key at a reasonable cost, which is durable and practical and is efficient when in use.

These being among the objects of the present invention, the same consists of certain features 35 of construction and combinations of parts to be hereinafter described and then claimed with reference to the accompanying drawing illustrating a desirable embodiment of the invention and wherein

40 Fig. 1 is a perspective view of such an improved key;

Fig. 2 is a detail sectional elevation of sufficient parts of a railway car truck to illustrate one possible use of the key, which is shown as being applied 45 to connect certain members of the truck together; and

Fig. 3 is a similar view showing the improved key in locking position.

In the drawing the improved key is shown as 50 relatively thin and flat at opposite surfaces, although it will be obvious herefrom that the key may be made of any desired cross-section, depending upon the use to which it is to be put. The key as shown is elongated and has a body 55 portion 5 which is preferably terminated by a

head 6 which extends laterally thereof. One longitudinal side or edge of the key-body 5 is provided with a relatively long notch or recess 7, which extends to about the middle of the key, while the opposite side or edge of the key is 60 formed with an incline 8 which is relatively offset with respect to the notch 7, so that beyond the body 5 the key is provided with a wedge-shaped portion 9 which is preferably straight on the side or edge just beyond the notch 7.

65 That wall of the notch 7 which is nearest to the wedge-shaped portion is inclined from the bottom of the notch towards the wedge-shaped portion, so that an inclined shoulder 10 is provided at this point. It will be noticed that the 70 inclined shoulder 10 is slightly in advance of the incline 8 of the key, such incline extending for substantially one-half of the length of the key, while the notch 7 is in the other half of the key. That end wall of the notch 7 which defines the 75 head 6 is or may be formed square so as to provide a square shoulder 11.

80 Preferably the wedge-shaped portion is formed with a slit at 12 or otherwise constructed, of suitable bendable metal, to bifurcate the key. This will enable the bifurcated portions 14 at 85 opposite sides of the slit or split 12 to be bent in opposite directions so as to act to more securely retain the key in position. At opposite sides of the slit or split 12 the terminals of the 90 wedge-shaped portion formed by the bifurcations are provided with beveled surfaces 13, 13a, extending cross-wise of the key, these bevels converging at the slit or split 12, to preferably provide a V-shaped recess. These bevels 95 13, 13a enable the point of a cold chisel, for example, to be inserted between the terminals of the bifurcated portions, at opposite sides of the slit 12, with a view to facilitating the introduction of the chisel into the slit, for bending the bifurcations away from each other. It will be obvious that the shoulder 11 of the notch 7 is not necessarily square, for if it is slightly rounded off it will facilitate its engagement by the point of a cold chisel, for example, with a view to draw 100 the key.

In Figs. 2 and 3 the key is shown for connecting members of a car-truck together, for example, as more specifically shown and described in co-pending application Serial No. 633,067, filed 105 September 14, 1932, of which the present application is a partial continuation and a division. In said figures a portion of a car-truck member 15 is illustrated, together with a bracket 16 which depends therefrom, such bracket being 110

provided with a foot portion 17. The bracket is apertured so that a safety bar 18 may pass therethrough and rest upon the foot portion 17, such safety bars being usually employed in car 5 trucks to serve as an emergency support for a brake beam in case it fails and drops. Through holes in the safety bar 18 and the foot 17, or through holes in other members to be connected, a bolt 19 is passed, such bolt being preferably 10 provided with an integral head 20 located above the safety bar. The bolt 19 has a through slot 21 which extends in a plane coincident with the longitudinal axis of the bolt, such slot being narrowed to slightly more than the thickness of the 15 improved wedge key, if the same be made thin and flat as illustrated in Fig. 1. Resilient means 22 in the form of a split washer having a single convolution is preferably placed under the head 20 of the bolt.

20 Fig. 2 illustrates how the improved wedge key acts in applying it to the bolt 19, where the wedge portion 9 of the key is shown as bearing directly upon the foot 17 or other member to which the bolt is applied. The small end of the wedge 25 of the key is first inserted into the slot 21 of the bolt, the key being placed in inclined position, with the inclined edge portion 8 presented towards the foot 17. The helical spring or washer 22 is placed under tension as soon as a slight 30 blow on the head 6 of the key has driven it into the slot 21 for a little distance, and as the key is further driven in, the spring 22 is still more compressed, so that when the key is driven in far enough so as to register the notch 7 with the unslotted end portion of the bolt, such end 35 portion snaps into the notch so as to interlock with the key, the spring 22 being then somewhat relieved of pressure and taking the position approximately as shown in Fig. 3.

40 Inasmuch as the key is of greater width transversely of the notch 7 than it is at the outer terminal of its wedge-shaped portion, the spring 22 is held under considerable pressure, in the 45 position shown in Fig. 3, and the strong tension of the compressed spring acting between the member or safety bar 18 and the head 20 of the bolt, binds such member to the member or foot portion 17 and insures a reliable locking together of the key and the bolt. Thus the connected 50 truck or other members will be strongly held together, allowing a very slight easing movement of the members, but so holding the members together as well as the attaching means, that no rattling of the assembled elements can take 55 place and no vibration which would cause disastrous wear or ultimate wear of the parts. The key when used in such connections tends to eliminate all wear; at least it materially extends the life of the assembled and connected elements.

60 In this connection it may be stated that continued vibration of such members connected by the improved key has been demonstrated in a test machine for at least approximately two thousand hours with no visible wear and no trou- 65 ble encountered.

Referring to the beveled surfaces 13, 13a at the smaller end of the key, it will be seen that they facilitate the spreading apart of the bifurcations 14, so that bolt may be more reliably held in position. When the key is in locking 80 position as shown in Fig. 3 a suitable blow on the smaller end of the key will facilitate its removal from the bolt, for at the same time the inclined shoulder 10 acts upon the outer end of the bolt to compress the spring 22, or, as is preferably done, the point of a cold chisel or the like 85 may be inserted between the bolt and the shoulder 11 and the key withdrawn by exerting the leverage thereof.

It is obvious that the invention herein disclosed is susceptible to modification without departing from the scope of the claims, one obvious modification being to construct such a flat key of two corresponding lengths and shapes of flat sheet 90 steel, which are connected together at the head end of the key by means of a suitable rivet.

What I claim as new is—

1. A wedge-key, comprising an elongated body which is inclined at one side along a portion of its length to provide a wedge-portion at one end 100 of the key, and the body having a longitudinal notch in its other end, extending along that side of the body opposite to the incline, the notch extending approximately as far as the inner end of the wedge-portion.

2. A wedge-key, comprising an elongated body which is inclined at one side along a portion of its length to provide a wedge-portion at one end of the key, and the body having a longitudinal notch in its other end, extending along that side 110 of the body opposite to the incline, that wall of the notch nearest the wedge-portion being inclined from the bottom of the notch outwardly toward the wedge-portion.

3. A wedge-key, comprising an elongated body 115 provided with a wedge-shaped end, and the body having a longitudinal notch in its other end, that wall of the notch nearest the wedge-shaped end being inclined from the bottom of the notch outwardly toward the wedge-shaped end.

4. A wedge-key, comprising a relatively thin and flat body with a head at one end, one edge of the key being inclined for a portion of its length to provide a wedge-portion at the other end of the key, and the key having a longitudinal notch in its other edge extending substantially the distance between the head and the wedge-portion.

5. A wedge-key, comprising a relatively thin and flat body with a head at one end, one edge of the key being inclined for a portion of its length to provide a wedge-portion at the other end of the key, and the key having a longitudinal notch in its other edge and located between the head and the wedge-portion, that wall 135 of the notch remote from the head being inclined from the bottom of the notch outwardly toward the wedge-portion.

SETH A. CRONE.
